US00D551577S

(12) **United States Design Patent** (10) **Patent No.:** **US D551,577 S**
(45) **Date of Patent:** **** Sep. 25, 2007**

(54) **THERMOSTAT HOUSING**

(75) Inventors: **Eric Barton**, Eden Prairie, MN (US);
Christian Trifilio, St. Paul, MN (US);
Paul Meyers, Fishers, IN (US)

(73) Assignee: **Honeywell International Inc.**,
Morristown, NJ (US)

(**) Term: **14 Years**

(21) Appl. No.: **29/276,632**

(22) Filed: **Jan. 31, 2007**

Primary Examiner—Antoine D. Davis

(57) **CLAIM**

The ornamental design for a thermostat housing, as shown and described.

DESCRIPTION

FIG. 1 is a front elevation view of a thermostat housing; and, FIG. 2 is a front elevation view of another thermostat housing.

The portions illustrated in broken lines on the figures are for illustrative purposes only and form no part of the claimed design.
